PROCESS FOR SPRAYING MATERIALS

Frederick R. Seavey, Albert J. Phillips, and
Fredrich Olsen, Dover, N. J., assignors, by
direct and mesne assignments, to The Cellulose
Research Corporation, a corporation of Dela-
ware

Application April 10, 1929, Serial No. 354,110

2 Claims. (Cl. 8—2)

This invention relates to a process and apparatus for coating sheet materials and the like and more particularly to a process and apparatus for treating paper and paper pulp with a bleaching solution.

Sodium bi-sulphite and other bleaching solutions for bleaching paper pulp and the like have been used heretofore but these solutions have been unsatisfactory because of the difficulty in uniformly distributing the solutions, the extreme care which must be utilized in handling some of the solutions because of their strong corrosive properties and the formation of crystals if and when the solutions are hot and nearly saturated.

The main object of this invention is to overcome these objectionable features in using bleaching solutions such as sodium bi-sulphite as a bleach for paper, paper pulps and the like and to provide a new and improved process and apparatus for evenly and uniformly distributing bleaching solutions over the surface of the paper pulp.

A further object of the invention is to provide a process for uniformly distributing the bleaching solution over the surface of the paper pulp in the form of a fine spray.

A further object of the invention is to provide a process and apparatus for coating paper or fabrics to produce decorative effects thereon.

In attaining these objects we provide a hood open at the bottom and provided with a mechanical means for converting the sodium bi-sulphite or other bleaching solution or coloring materials into a fine spray with baffle means to catch any large drops of bleaching solution or coloring materials in order to prevent them falling upon the surface of the paper pulp or other sheet material where they would cause spots because of the concentration of bleaching solution therein or concentration of coloring material.

Other objects and advantages will be apparent from the following specification and accompanying drawing, in which

Fig. 1 is a diagrammatic view of one form of apparatus for carrying out the process of this invention.

Fig. 2 is a sectional view of the apparatus shown in Fig. 1.

Fig. 3 is a sectional view of another apparatus for carrying out the process of this invention.

Fig. 4 is a horizontal sectional view taken on line 4—4 of Fig. 3, and

Fig. 5 is an enlarged detailed view of the distributor of the apparatus shown in Figs. 3 and 4.

In the apparatus for carrying out this process shown in Figs. 1 and 2 a hood 10 is formed from sheet material having preferably a rounded top and perpendicular side and end portions with an open bottom portion beneath which the sheet material 11 to be bleached or colored, such as a sheet of paper pulp, paper or fabric, is passed. Upon either side of the hood 10 are located a series of spray nozzles 12 of non-corrosive material, if bleaching solutions are used, such as bakelite or resistive alloys having an inlet 13 for the bleaching solution or coloring material and an air inlet 14. The air atomizes the bleaching solution or coloring material and it passes from the nozzle in a fine spray which uniformly and evenly contacts with the surface of the sheet of paper pulp or other material as clearly shown, bleaching or coloring the same uniformly as it passes beneath the hood. The temperature of the bleaching solution or coloring material has a decided effect upon the size of the drops of the liquids.

It is of extreme importance that drops of bleaching solution or coloring material of sufficient magnitude to contain a concentration of bleaching solution or coloring material in excess of that produced by the spray nozzles be prevented from contacting with the sheet of paper pulp or other material. For this purpose a series of baffles 15 are provided within the hood which extend completely around the hood and may progress in width as they near the bottom of the hood, catching any drops from the spray nozzles which, due to their larger mass, will be thrown to the sides of the hood. These baffles 15 are spaced from the sides of the hood and supported on brackets 16 secured to the sides of the hood so that the accumulated bleaching material or coloring material will flow downwardly from one to the other. The rounding of the top of the hood also prevents accumulation of drops thereon as the bleaching material or coloring material therefrom runs down the sides of the hood and does not accumulate in drops. The drops from the baffles are collected by a drip pan or collecting trough 17 located on the inside of the hood which is connected to a storage tank for the bleaching solution or coloring material by pipe connection 18.

In bleaching paper and in coating or coloring many types of objects, it is frequently imperative to avoid the application of large drops to these materials, since a large drop of bleaching

liquor will produce an uneven whitening, a large drop of colored fluid will produce an undue concentration of color at the place of application. This invention provides a means whereby large drops may be separated from the small and desired drops by the use of a series of baffles 15.

In the apparatus shown in Figs. 3, 4 and 5 the process is carried out within a cylindrical hood 19 provided with an open bottom and progressive baffle plates 20 circling the inside of the hood from which the drops collected thereby flow to the collecting trough 21 on the inside of the hood.

The atomizing of the bleaching solution or coloring material is carried out by means of a rapidly rotating horizontal spray wheel or wheels 22 provided with an oblique edge 23 which is ribbed or serrated to provide points to break up the bleaching solution or coloring material into fine particles to form a fine spray as it is thrown outwardly by centrifugal force. The spray wheel 22 is conveniently secured rigidly to the end of the shaft 24 of the motor 25 which extends through the top of the hood 19. The motor is held in position by a frame work 26 secured to the top of the hood 19. The bleaching solution or coloring material is fed to the spray wheel 22 by means of a feed pipe 27, one end of which extends through the top of the hood 19 and terminates in close proximity to the center of the spray wheel.

The size of the drops and the intensity of the mist or spray may be regulated by the rate at which the liquid is dropped upon the wheel, the peripheral speed and position of the wheel and the form of the wheel and temperature of the liquid. Further regulation may be provided by the use of more than one feed pipe and the use of more than one wheel or the change in position 40 of inlet pipe above spray wheel.

Decorative effects upon paper or fabrics may

be created by this process and apparatus, for example a sheet material having lighter bands of coloring material than the remainder of the coated surface can be made by the insertion of baffle troughs such as shown in dotted lines at 28 extending from the lower collecting trough 17.

While the invention is illustrated and described more particularly with reference to a process and apparatus for bleaching or coloring materials, the invention is not confined thereto but is intended to cover any other bleaches, coloring materials or apparatus suitable for carrying out the process and any other uses or modifications within the scope of the appended claims.

We claim:

1. The process of treating sheet materials which consists in spraying a fluid treating medium into a chamber in opposite directions and toward opposite sides, trapping any large drops of spray on each side while leaving an unobstructed center space below the entry of said spray, and permitting the resultant fine, evenly divided spray to pass down through said center space and contact with the materials to be treated.

2. The process of treating sheet materials which consists in spraying a fluid treating medium into a chamber in opposite directions and toward opposite sides so that said sprays cross each other near the center of said chamber, trapping any large drops of spray on each side while leaving an unobstructed center space below the entry of said spray, and permitting the resultant fine, evenly divided spray to pass down through said center space and contact with the materials to be treated.

FREDERICK R. SEAVEY.

ALBERT J. PHILLIPS.

FREDRICH OLSEN.
